UNITED STATES PATENT OFFICE

HAROLD F. WATKINS, OF OAKLAND, CALIFORNIA, ASSIGNOR TO WATKINS INTERMITTING PUMP CO., OF SAN FRANCISCO, CALIFORNIA, A CORPORATION OF CALIFORNIA

WELL PUMP

Application filed August 8, 1927. Serial No. 211,839.

This invention relates generally to pumps for lifting liquids from deep wells and is especially applicable for pumping oil.

It is a further object of this invention to incorporate means in a pump of the plunger type for aiding in lifting the column of liquid above the pump plunger, thus minimizing the power required to reciprocate the plunger and reducing the wear upon the plunger and pump valves.

It is a further object of this invention to incorporate the principle of introducing recurrent charges of compressed gas into the lower portion of a pump barrel in order to aid the normal operation of a pump of the plunger type.

Further objects of this invention will appear from the following description in which I have set forth the preferred embodiment 20 of my invention.

Referring to the drawing:

Figure 1 is a side elevational view showing the invention applied to an oil well.

Fig. 2 is a cross sectional detail showing 25 the auxiliary valve mechanism which I propose to incorporate with a plunger pump.

Fig. 3 is a cross sectional detail showing a representative pump with which my invention may be incorporated.

30 Fig. 4 is a detail illustrating a modification of the auxiliary valve mechanism.

The invention may be outlined briefly as comprising auxiliary means in conjunction with a liquid pump of the plunger type, for introducing recurrent charges of compressed gas into the pump barrel directly above the pump plunger. These charges of gas form in effect pneumatic pistons which lift the column of liquid in the discharge pipe, thus 35 minimizing the lifting force exerted by the pump plunger. The auxiliary means is preferably in the form of a valve cooperatively associated with a hollow sucker rod. Compressed gas is introduced into the plunger 40 rod from the surface of the well and reciprocating movements of the rod serve to open and close the auxiliary valve to control introduction of the gas charges.

Referring to the drawing for a more complete description, there is shown in Figs. 1

and 3 a conventional form of deep well pump such as are commonly used in oil wells. Such a pump comprises for example a pump barrel 10 within which one or more pump plungers 11 are operatively disposed. Associated with the lower portion of the barrel, there is a standing or check valve 12, while movable with the plunger 11, there is the usual lift valve 13. The barrel is lowered into a well 14 with the standing valve substantially below the normal liquid level, and the plunger is usually reciprocated by means of a solid sucker rod which is attached to the upper end of valve 13.

In this invention the sucker rod 16 is in the form of a pipe or tube, or in other words it is hollow to permit passage of compressed air or other gas. The upper end of this hollow sucker rod is connected with suitable mechanism for reciprocating the same, and is also in communication with a source of gas under pressure as by means of pipe 17. In that form of the invention shown in Fig. 1, instead of connecting the hollow sucker rod 16 directly to the valve 13, it is connected thru an auxiliary valve mechanism indicated generally at 18.

That form of the auxiliary valve mechanism 18 illustrated is to be preferred because of its simplicity, and comprises a sleeve 19 provided with coupling means 21 at its lower end for making connection to the valve 13. Slidably fitted within the sleeve 19, there is a cylindrical valve member 22 which is adapted to reciprocate thru a limited stroke within the sleeve 19. Extending upwardly from the valve member 22, there is an actuating rod 23 which is adapted to be connected to the lower end of hollow sucker rod 16 as by means of coupling 24. Gas which is introduced into the upper portion of hollow sucker rod 16 may pass downwardly thru passage-way 26 provided in rod 23, and thru one or more ports 27 provided in valve member 22. Ports 27 are adapted to cooperate with one or more ports 28 provided in sleeve 19, whereby when valve member 22 is at the lower limit of its movement relative to sleeve 19, gas from the hollow sucker rod is discharged into the pump barrel thru ports 27 and 28, but dis-

charge of gas is interrupted when valve member 22 is at the upper limit of its stroke. For limiting the upward movement of valve member 22 with respect to sleeve 19 I have shown a guide member 29 secured to the upper end 5 of sleeve 19. Relative rotation between valve member 22 and sleeve 19 is prevented by providing a key 31 which is fixed with respect to sleeve 19, and which engages a groove 32 in valve member 22.

10 When the pump as described above is in operation, at the beginning of a down stroke of hollow sucker rod 16, valve member 22 first moves downwardly into the sleeve 19 to bring 15 ports 27 and 28 into registry and thus permit the discharge of compressed gas into the pump barrel directly above the plunger 11. Further movement of rod 16 forces the plunger downwardly and during this downward 20 movement gas is continually discharged. On the upstroke of rod 16, the first result is to move valve member 22 upwardly within sleeve 19 to interrupt discharge of gas into the pump barrel. Further movement of the 25 sucker rod lifts the pump plunger which then operates in its usual capacity to lift the upper column of oil. Thus during continual operation of the pump, charges of gas are 30 continually introduced into the column of oil above the pump plunger and these charges act as pneumatic pistons which in addition to the lifting effect on plunger 22, lift the column of oil and cause its discharge at the 35 top of the well. Because the compressed gas is introduced into the oil column in the form of recurrent charges, the oil will not be emulsified as would be the case if the gas were continually introduced into the oil column. Because of the lifting effect of the gas charges, 40 the plunger and valves of the pump are relieved of a substantial amount of hydrostatic pressure. Thus leakage and wear of these parts is minimized and the pump will 45 operate with high efficiency. As there is a substantial reduction in the power required to operate a pump of this kind, it is feasible with a given installation to substantially increase the pumping capacity of a given installation by increasing its speed of operation.

50 In Fig. 4 I have illustrated a modification of the invention in which the pump barrel forms one of the elements of the auxiliary valve. In this case the plunger valve 36 has 55 a special cage 37 which is directly connected to the hollow sucker rod 16 as by means of coupling 38. The upper portion of cage 37 is provided with one or more ports 39 communicating with a passage 41 thru which gas 60 may be introduced from hollow sucker rod 16. The inner wall of the pump barrel 100 is provided with an angular groove or recess 42 adapted to cooperate with ports 39. A 65 plurality of grooves 43 communicate between the annular recess 42 and the barrel 100 above

the valve cage 37. At the lower portion of the down stroke of hollow sucker rod 16, ports 39 are brought into registry with the annular groove 42, thus permitting discharge of compressed gas from the hollow sucker 70 rod into the pump barrel thru grooves 43. When the sucker rod is moved upwardly port 39 is brought out of registry with recess 42 and introduction of gas is interrupted, since grooves 43 are not adapted to register 75 with ports 39. The operation of this pump is substantially identical to that shown in Fig. 1 with the exception that gas is introduced only at the lower portion of the stroke rather than during the down stroke. 80

It is obvious from the above description that I have devised a novel pumping device in which the idea of discharging recurrent charges of compressed gas into a well, is correlated in a novel manner with the mechanism of a standard reciprocating plunger 85 pump.

The operation of the standing valve, pump plunger, and plunger valve causes intermittent inflow of oil from the well into the 90 plunger, and in the invention described above, the gas is introduced at a time when no inflow is occurring. By operating the auxiliary valve in this manner, I prevent emulsifying of the oil by the gas which is 95 introduced.

I claim:

1. In an oil well pump, a pump barrel, valve and plunger mechanism operatively disposed within the barrel and adapted to be reciprocated, a hollow sucker rod for reciprocating said mechanism, a source of gas under pressure associated with the upper portion of the rod, and additional valve means associated with the lower portion of the rod and operated by reciprocation of the rod to introduce recurrent charges of gas into the barrel. 100

2. In an oil well pump, a pump barrel, valve and plunger mechanism operatively disposed within the barrel and adapted to be reciprocated, a hollow sucker rod for reciprocating said mechanism, a source of gas under pressure associated with the upper portion of the rod, and valve means associated with the lower portion of the rod above said mechanism, said valve means being operable to admit a charge of gas into the barrel upon movement of the rod in one direction. 110

3. In an oil well pump, a pump barrel, a standing valve associated with the lower portion of the barrel, a pump plunger disposed within the barrel, valve means associated with the plunger for effecting lifting of liquid in conjunction with the standing valve, a hollow sucker rod adapted to extend down into a well and secured to said plunger for reciprocating the same, and an auxiliary valve disposed near the lower end of the rod and above the plunger, said auxiliary valve 120 125 130

being adapted to alternately establish and interrupt communication between the barrel and said hollow rod during normal operation of the pump.

- 5 4. In an oil well pump, a pump barrel, a standing valve associated with the lower portion of the barrel, a pump plunger disposed within the barrel, valve means associated with the plunger for effecting lifting
- 10 10 of liquid in conjunction with the standing valve, a hollow sucker rod adapted to extend down into a well and secured to said plunger for reciprocating the same, a source of gas under pressure connected to the upper portion
- 15 15 of the rod, and auxiliary valve means associated with the lower portion of the rod above said plunger, said auxiliary valve means being operated by reciprocating movement of the rod whereby upon movement of the rod in one direction, said auxiliary valve is closed, while upon movement of the rod in the opposite direction, the auxiliary valve is opened to permit a charge of gas to enter the barrel.
- 20 25 5. In an oil well pump, a pump barrel, valve and plunger mechanism operatively disposed within the barrel and adapted to be reciprocated, a hollow sucker rod for reciprocating said mechanism, a source of gas under pressure connected with the upper end
- 30 35 of said rod, and valve means associated with the lower portion of said rod for controlling communication between said rod and barrel, and means for effecting opening and closing movements of said valve to introduce recurrent charges of gas into the barrel.
- 40 6. In an oil well pump, a pump barrel, valve and plunger mechanism operably disposed within the barrel and adapted to be reciprocated, valve means within the well and associated with said mechanism, a source of gas under pressure communicating with said valve means, and means for reciprocating said mechanism and for recurrently opening and closing said valve means, said valve means serving to intermittently introduce gas under pressure into the well to lift oil therefrom.
- 45 50

In testimony whereof, I have hereunto set my hand.

HAROLD F. WATKINS.
